FIG. 1 is a front, top and side perspective view of the fire hose gripping clamp showing my new design;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof; and,

FIG. 7 is a bottom plan view thereof.

FIG. 4.

FIG. 2.

FIG. 5.

FIG. 3.

FIG. 7.

FIG. 6.
